CLAIM

The ornamental design for a bread bun, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of a bread bun showing my new design;

FIG. 2 is another top plan view thereof;

FIG. 3 is a side perspective view thereof;

FIG. 4 is another side perspective view thereof;

FIG. 5 is another perspective view thereof;

FIG. 6 is a top perspective view thereof, shown in an alternate position;

FIG. 7 is a top plan view thereof, shown in an open position;

FIG. 8 is a perspective view thereof, shown in an open position;

FIG. 9 is a top plan view of the bottom portion of the bread bun;

FIG. 10 is a side perspective view of the bottom portion of the bread bun; and,

FIG. 11 is another side perspective view of the bottom portion of the bread bun.
